SUPPORT UNIT FOR ABOVE-GROUND SWIMMING POOLS OR THE LIKE

William A. Oden, Upland, Calif., assignor to Domain Industries, Inc., New Richmond, Wis.

Filed June 21, 1973, Ser. No. 372,284

Term of patent 14 years

Int. Cl. D25—99

U.S. Cl. D13—1 G

FIG. 1 is a side elevation showing a unit support of my improved design;

FIG. 2 is a perspective view of the same;

FIG. 3 is a rear elevational view of said embodiment;

FIG. 4 is a front elevational view of the same;

FIG. 5 is a top plan view of the same; and

FIG. 6 is a bottom plan view of the same.

I claim:

The ornamental design for a support unit for above-ground swimming pools or the like, as shown.
